UNITED STATES PATENT OFFICE.

JOSEPH A. SHOEMAKER, OF BROOKLYN, NEW YORK.

GARMENT HANGER.

Original application filed April 22, 1921, Serial No. 463,452. Divided and this application filed January 7, 1922. Serial No. 527,580.

To all whom it may concern:

Be it known that I, JOSEPH A. SHOEMAKER, a citizen of the United States, residing at Brooklyn, in the county of Kings 5 and State of New York, have invented certain new and useful Improvements in Garment Hangers, of which the following is a specification.

This invention relates to garment hangers 10 and has for its primary object to provide a closing hanger having means to support the coat of a suit or dress, and a supporting cross bar for the trousers or skirt of the suit, the parts being constructively arranged to permit of the folding of the 15 hanger for convenience in packing.

Another object of the invention is the construction of a hanger wherein the cross bar for supporting the trousers or skirt is 20 in the form of a clamping member whereby the garment may be properly supported and prevented from creasing or wrinkling.

Another and very important object of the invention is the provision of a folding 25 garment hanger of the type above set forth wherein the skirt or trouser supporting member is in the nature of a clamp and adapted to be suspended from the supporting bars so that a number of garments may 30 be hung thereon without interfering with the coat portion of the suit.

Another and very important object of the invention is the construction of a folding hanger of the type above set forth consisting of comparatively few parts, extremely 35 simple, strong and durable, rigid and capable of being manufactured at an extremely low cost whereby its commercial possibilities are greatly enhanced. The subject matter of this invention is a part of my invention for garment hangers filed April 22nd, 1921, Serial Number 463,452, of which this is a division.

I attain the above objects and others by 45 the accompanying drawings, wherein:

Figure 1 is a view in front elevation of a garment hanger embodying the clamping member and showing the device in extended position.

Figure 2 is a view of the same in folded position.

Figure 3 is a view in edge elevation of the hanger.

Figure 4 is a detailed view in transverse 55 section of a connection.

Figure 5 is a view of said connection in side elevation,

Figure 6 is a view in perspective of the hanger clamp in open position, and

Figure 7 is a detailed view in section of the saddle connection.

Referring now to the drawings wherein like reference characters designate corresponding parts throughout the several views, 10 and 11 indicating the coat supporting members of the hanger consisting of straight bars having their adjacent inner ends cut away for overlapping connection and an element penetrating said ends to pivotally 15 connect the members which element is preferably in the form of wire and bent to form a hook whereby the entire device may be suspended. At the outer ends of the members 10 and 11, I have provided a 20 double eye clip, shown in detail by Figures 4 and 5 and consists of a single strip of metal bent double and having its ends separated to form the U-shaped portion 24 embracing the member 10 and the dividing 25 portion 25. Incisions in the strip are made 30 so that the two portions of the material may be dug out to form eyes 26, one at each side of the dividing portion. A rivet 27 or other fastening element extends through the U-shaped portion of the member 10. 35 Two links 28 and 29 are provided at each end of the hanger, each of said links consisting of a strand of wire having its ends looped as at 30 and 31. The loops 30 are 40 interlinked with the eyes 26 while the loops 31 embrace pins 32 which are mounted in the ends of the clamping bars 33 and 34. Said pins also extend through the U-shaped 45 clips 35 between the sides of which the loops 31 are held. Pins 36 extend across the 50 clips 35 to form a pair of stops. A ring 37 encircles each pair of links 28 and 29.

The unfolding movement of the hanger is of course limited by engagement of the links against the pins 36. To insert a garment in the clamp, the hanger is laid upon one side as shown in Figure 6 and the rings 37 moved toward the double eye clips, thus permitting one clamping bar 33 or 34 to be moved upward to a self sustained elevated position. The edge of the garment is laid upon the lower clamping bar and the other moved downward and the rings 37 again shifted toward the clamping bars to bind the latter against the garment. The 55

clamping bars may be separated to the limit of movement by slipping the rings 37 over the eyes 26 of the double eye clips. It will be noted that while there is more or less universal movement permitted between the links and the members 10 and 11, nevertheless when the clamping bars are bound together, the relative sidewise movement between the members 10 and 11 and the 10 clamping bars is limited, thus preserving the form of the hanger. Attention is also directed to the fact that when the hanger is extended, its premature collapse while adjusting a garment thereon is effectually prevented when separating one clamping bar from the other and holding the same. Similar to my parent application the combined lengths of the coat supporting members 10 and 11 are greater than the length of 20 the trouser supporting member or clamp above described consisting of the two bars 33 and 34. Moreover it should be noted that the links 28 and 29 are of such a length that when the hanger is in its open position sufficient space is provided to permit of a 25 number of garments to be hung and suspended on the supporting bars 33 and 34 when the same are not used as a clamping member.

30 In the accompanying drawings, I have illustrated my invention embodied in one form by way of example, and which construction has been found to answer to a satisfactory degree the results to be obtained. It would be manifest, however, that 35 other forms of embodiment may be adopted, and that the construction may be variously changed and modified by the skilled mechanic without departing from the limits of 40 the invention. Further it will be understood that the invention is not limited to any particular form of construction in the parts, except in so far as such limitations

are specified in the subject matter being 45 claimed.

Having thus described my invention, what I claim as new, and desire to secure by United States Letters Patent is:

1. A garment hanger including a pair of pivoted bars, a pair of suspended links attached to the outer end of the bars and movable to either side thereof, a pair of clamping bars connected to the opposite ends of the links, said pivoted bars and clamping bars being adapted for relative movement so that they lie in parallelism and contiguous to each other when the hanger is collapsed. 50

2. A garment hanger of the character described including two members pivoted together at an end of each, a pair of clamping bars of less length than the combined length of the two members and links connecting each end of said clamping bars with a corresponding free end of said members 65 so that the said pivoted members and clamping bars may lie contiguous to each other and in parallelism when the hanger is folded. 60

3. A garment hanger of the characters described including two members pivoted together at an end of each, a pair of clamping bars of less length than the combined length of the two members, a pair of links connected at each end to the respective ends of the pivoted members and clamping bars, said pairs of links having a sliding ring thereon for clamping the bars together when in their extended positions, said pivoted members and clamping bars being movable 75 relative to each other whereby they may be disposed in contiguous parallel relation 80 when the hanger is collapsed. 70

In testimony whereof I affix my signature.

JOSEPH A. SHOEMAKER.
